ELECTRIC IRON

Paul J. McCullough, St. Louis, Mo., assignor to
Joseph Pavella, Sr., St. Louis, Mo.

Application March 30, 1936, Serial No. 71,401

18 Claims. (CL 218--35)

This invention relates to electrically heated smoothing irons and consists in novel construction and arrangement of the thermostatic control mechanism and associated parts whereby the current for the heating element is controlled.

In the conventional type of iron with automatic control of the current, there is at times considerable difference in temperature between the surface of the iron and the thermostatic member relied upon to control the supply of current. This is particularly true where the thermostatic member is spaced from the ironing surface, or is surrounded by a substantial volume of air, or otherwise insulated from the ironing surface. Frequently the thermostatic member is affected more readily by the temperature of and surrounding the heating element rather than by the temperature of the portion 20 of the iron applied to the article being ironed.

Obviously such arrangements do not make for accurate or efficient operation of the thermostat, and one object of the present invention is to correlate an ironing surface, the thermostatic control, the heating element, and the parts actuated thereby so that each will possess a high degree of efficiency from the standpoint of operation, simplicity of construction, and length of life, etc.

Another object of the invention is to simplify the manually operated device for varying the temperature of the iron and, incidentally, to give the iron a neat, attractive appearance notwithstanding the mounting of the manual control in the handle and the necessity of connecting such a control to mechanism in the iron casing.

Another object of the invention is to simplify the assembly of the heating element with the iron sole plate and at the same time to provide 40 efficient distribution of heat from the element to the sole plate.

These and other detail objects which will be apparent from the following description are obtained from the structure illustrated in the 45 accompanying drawing, in which—

Figure 1 is a vertical longitudinal section through an iron of the type described, a portion of the structure being shown in elevation.

Figure 2 is a horizontal section taken substantially on the line 2—2 of Figure 1.

Figures 3 and 4 are vertical transverse sections taken on the lines 3—3 and 4—4, respectively, of Figure 1, Figure 3 showing the parts in a different position than indicated in 55 Figure 2.

Figure 5 is a fragmentary view of the switch parts in a different position, and is taken on line 5—5 of Figure 3.

The sole plate 1 has the usual flat iron contour and preferably consists of a simple slab 5 of metal of substantial thickness and free of upstanding ribs or depressions requiring special molding or machining operations except that an elongated cylindrical hole 2 is drilled inwardly from one edge of the sole plate to receive and 10 closely enclose a thermostatic member 3.

An electric heating element 4 of familiar resistance grid type overlies the top face of sole plate 1 extending substantially throughout the length of the iron and preferably is made in 15 two sections spaced apart across the iron. A relatively light metal sheet 5 extends over heating element 4 with its edges offset downwardly, as at 6, to contact with the sole plate. Preferably sheet 5 has an intermediate depression 7 20 also contacting with the sole plate in the space between the sections of grid 4.

Current is brought to the terminals 8 and 9 by any usual plug. Conduit 10 leads from terminal 8 to one end of the heating grid. Conduit 11 leads from the other end of the grid to the binding post 12. Switch blades 13 and 14 of spring material are insulated from each other at their right hand ends and have contact buttons 15 and 16, respectively, on their left hand ends. Blade 13 is connected to binding post 12 and blade 14 has a connection 17 to terminal 9. Normally the spring action of blades 13 and 14 is to thrust each of these blades in an anti-clockwise direction as indicated by the arrow A. 30

Thermostatic member 3 comprises a bi-metallic helix of familiar type although not previously used in electric irons, so far as I am informed. Each end of member 3 is provided with a longitudinal slot, and a pin 18 has the 40 inner face of its slotted head seated against the edge of the sole plate surrounding the outer end of hole 2 with the inner end of the pin provided with a lip 19 fitting into the corresponding slot in member 3. A finger 20 has its lower end 45 fitted into the slot in the right hand end of member 3 and extends upwardly through the top of the sole plate through sheet 5 and into contact with an insulation roller 21 carried on the outer end of blade 13. A screw 22 (Figure 50 4) is threaded into the edge of sole plate 1 with its head overlapping the head of pin 18 whereby pin 18 and the adjacent end of the thermostatic member may be anchored to the sole plate. 55

As member 3 is heated, its bi-metallic construction causes it to twist so that its opposite ends rotate about its axis in opposite directions. With the right hand end being held against 5 rotation, particularly in an anti-clockwise direction as indicated at X in Figure 4, the left hand end, carrying finger 19, tends to rotate in a clockwise direction as indicated by the arrow B in Figure 3. Such rotation of finger 10 15 will move blade 13, against its spring tendency, to separate contacts 15 and 16 as indicated in Figures 3 and 5.

Upon cooling, the thermostat tends to return to its original position. Switch blade 14 is released at 14a to provide clearance for finger 19 so that stresses in the thermostat may be fully relieved. By loosening screw 21 and rotating pin 18, thermostatic member 3 may be adjusted axially to vary the temperature at which it 20 opens the switch or permits the switch to close.

When finger 19 and blade 13 are engaged, the reaction of the pressure between them will thrust member 3 against the side of hole 2, creating sufficient friction to retard free twisting 25 movement of member 3 and resulting in a lag between alternate movements of the thermostatic member and its finger. This avoids fluttering of the switch contacts and rapid opening and closing of the circuit, which is objectionable because of resulting annoyance in reception 30 of radios which may be on the same house circuit.

A sheet metal casing 22 is applied to the sole plate and encloses the heating element, switch 35 structure, etc., forming a substantial air chamber above the heated parts and giving the iron an attractive appearance. It is braced near the middle of the iron by a support 31. A handle 23 is carried on casing 22, the rear bow of the 40 handle merging in a guard socket 24 for receiving the usual plug which is applied to terminals 8. The front portion or bow of the handle curves downwardly in an arc 25 of a circle. A portion of this part of the handle is 45 hollow to form a chamber which receives a rigid segmental bar 26 slideable in the handle from the position shown in full lines in Figure 1 to the position shown in dot and dash lines. S indicates a spring frictionally engaging bar 26 50 to resist its accidental movement.

A slot 27 leads from the hollow interior of the handle and a boss 28 on the upper end of bar 26 projects through slot 27 so as to be readily engaged by the thumb of the user of the iron. 55 The lower end of bar 26 forms a horizontally wedge-like structure 29, one edge of which slides along a bearing 30 formed on casing support 31. The other edge of wedge 29 engages an insulation roller 32 having a vertical axis and mounted 60 on an extension 33 on switch blade 14.

Obviously movement of boss 28 in the direction of the arrow C moves wedge 29 in the opposite direction and thrusts blade 14 in a direction opposite to arrow A, thereby moving blade 65 13 (if buttons 15 and 16 are in contact) away from finger 19 of the thermostat, whereby higher temperature will be required to produce the greater movement of the thermostat necessary to separate contacts 15 and 16. Subsequent 70 cooling of the thermostat and return movement of finger 19 and blade 13 will close the switch sooner than with wedge 29 retracted and accordingly maintain a higher temperature for the iron as may be required for ironing heavier 75 material.

Preferably a tail 34 projects from boss 28 and closes the bottom of slot 27 as the boss is moved forwardly.

The rear of casing 22 extends beyond the rear end of sole plate 1 and terminates in a heel 35 which meets a finish strip 36 extending upwardly from the bottom of sole plate 1 to the end of heel 35. A wire bail 37 loosely mounted on plate 8 between heel 35 and strip 36 cooperates with guard 24 for supporting the iron when it 10 is stood on end temporarily while the material to be ironed is being adjusted. In this position elements 35 and 36 are spaced from the ironing board or table.

Although strip 36 affords a neat finish for 15 the lower rear portion of the iron, the notch or opening 38 therein provides access to screw 21 and plug 18 whereby the latter may be adjusted to set the thermostat operation as desired.

The construction described is simple and free 20 of a multiplicity of jointed members particularly in the connection between the switch adjustment and the control boss 28. The adjustment device in the present iron comprises a single rigid bar mounted on the handle and therefore 25 easily assembled with the casing and switch mechanism.

Obviously the particular arrangement of the switch parts and the details of the thermostat and its finger, the adjusting switch and the elements engaged thereby, are not essential to all features of the invention and these and other details may be varied without departing from the spirit of the invention and the exclusive use of such modifications as come within the 35 scope of the claims is contemplated.

I claim:

1. In an electric smoothing iron, a sole plate, a light metal sheet overlying said sole plate and cooperating with the top face thereof to form a 40 shallow housing, a heating element enclosed in said housing, and a thermostatic member for controlling current to said element located beneath said top face of said sole plate and between said element and the smoothing surface of 45 said sole plate.

2. In an electric smoothing iron, a sole plate, a web-like heating element overlying said sole plate, a thin sheet metal cover for said element cooperating with the top face of said sole plate 50 to form a housing for said element, a switch above said cover, a thermostatic member enclosed in said sole plate below said cover, and a switch actuating element extending through said cover and the top part of said sole plate and operatively engaged by said thermostatic member.

3. In an electric smoothing iron, a sole plate having a long narrow hole leading inwardly horizontally from one edge thereof and located below the top face of said sole plate, a heating element overlying said sole plate, an electric circuit therefor including a switch having a finger projecting downwardly into said hole, an elongated thermostatic member inserted in said hole through the end thereof in said edge until enclosed in said hole and comprising a bi-metallic helix with one end anchored to said sole plate adjacent to said edge and the other end operatively connected to said finger.

4. In an electric smoothing iron, a sole plate 70 having a hole leading inwardly from one edge thereof, a heating element overlying said sole plate, an electric circuit therefor including a switch, an elongated thermostatic member inserted in said hole and lying adjacent to one side 75

- thereof, said member comprising a bi-metallic helix with one end anchored to said sole plate and the other end operatively connected to said switch, the parts of said helix being so disposed that heat actuated rotary movement of said member moves a part of said switch and the reaction on said member thrusts it against the side of said hole to frictionally retard the rotary movement of said member.
5. In an electric smoothing iron, a sole plate, a heating element applied thereto, an electric circuit for said element having a switch with an adjustable contact adjacent to said sole plate, a casing enclosing said switch, a handle having an arcuate bow portion mounted on said casing, an inflexible member on said handle mounted to slide longitudinally thereof and provided with an arcuate extension housed within said handle portion and projecting into said casing and operatively connected to said contact.
10. 6. In an electric smoothing iron, a sole plate of the usual contour, a heating element overlying said sole plate, a thermostatic member enclosed in said sole plate, a finger connector to said member and projecting upwardly from said sole plate near the center thereof, a switch for controlling current to said element and including a movable part engaged by said finger, a casing mounted on said sole plate and housing said element, finger and switch, a handle having a bow curving from one end downwardly and inwardly to said casing, and an arcuate arm slidably mounted in said bow with its lower end terminating adjacent to said finger and part for regulating said switch and with its upper end terminating in a manually engageable device movable along the front portion of said handle.
15. 7. In an electric smoothing iron, a sole plate, a heating element, a thermostatic member for controlling the supply of current to said heating element, a handle provided with a hollow portion, there being a slot in the face of said handle leading to said hollow portion, an inflexible bar slidable in said hollow portion and having a boss projecting through said slot for manual manipulation of said bar, said bar including a part closing said slot in front of and at the rear of said boss, and means actuated by said bar to vary the operation of said thermostatic member.
20. 8. In an electric smoothing iron, a sole plate having a hole leading inwardly from one edge thereof, an electric heating element, a circuit therefor, a thermostatic member for controlling said circuit and inserted in said hole and comprising a bi-metallic helix, with a transverse slot in its outer end, and an anchorage for said outer end comprising an axially adjustable pin and a holding screw therefor seated against
- said sole plate edge, said pin having a lip entered in said slot.
9. In an electric smoothing iron, a sole plate having a hole leading inwardly from one edge thereof, an electric heating element, a circuit therefor, a thermostatic member inserted in said hole and comprising a bi-metallic helix, with a transverse slot in each of its ends, means for adjustably holding the outer end of said member against rotation comprising a part having a lip in said slot and a screw seated against said edge and clamping said part, and means for controlling said circuit including a finger fitting in the slot at the other end of said member and movable by axial rotation of said other end of said helix.
10. 10. In an electric smoothing iron, a sole plate, a bi-metallic thermostatic member enclosed between the top and bottom of said sole plate, an electric resistance heating element for said sole plate, a circuit therefor, and means actuated by deformation of said thermostatic member irrespective of the expansion and contraction of the surrounding sole plate for controlling said circuit.
15. 11. In an electric smoothing iron, a sole plate, a thermostatic member enclosed between the top and bottom of said sole plate and comprising a bi-metallic helix, an electric resistance heating element, a circuit therefor, and means actuated by heating and cooling of said helix for respectively opening and closing said circuit to control the supply of current to said element irrespective of the expansion and contraction of the surrounding sole plate.
20. 12. In an electric smoothing iron, a sole plate, an electric resistance heating element associated therewith, a thermostatically operated switch for controlling the electric circuit of said element and including a member adjustable to different positions to open and close said circuit at different temperatures, a handle spaced substantially above said sole plate element and switch, and a manually movable inflexible device extending from said member to the upper portion of said handle, every part of said device being movable in the arc of an upright circle.
25. 13. In an electric smoothing iron, a sole plate, means for heating said sole plate, a handle for manipulating the iron, said handle including a hand hold spaced above said sole plate and an arcuate portion between said hand hold and the sole plate, a manually adjustable inflexible device adjacent said hand hold, and an arcuate member operatively connecting said element to said means and movable in said arcuate portion along the line of its arc.

PAUL J. McCULLOUGH.
